UNITED STATES PATENT OFFICE

VIRGINIA HAMILL, OF NEW YORK, N. Y., ASSIGNOR TO THE PALMER BROTHERS CO.,
OF NEW LONDON, CONNECTICUT, A CORPORATION OF CONNECTICUT

DESIGN FOR A TEXTILE FABRIC

Application filed October 19, 1929. Serial No. 33,112. Term of patent 3½ years.

To all whom it may concern:

Be it known that I, VIRGINIA HAMILL, a citizen of the United States of America, and a resident of the borough of Manhattan, city, county, and State of New York, have invented a new, original, and ornamental Design for a Textile Fabric, of which the following description, in connection with the accompanying drawing, is a specification.

The single figure of the drawing is a plan view of a textile fabric showing my new design in which each of the blocks showing the outline of the motif in dotted lines appear in the actual fabric in the form illustrated in the center upper block as well as the color indicated shown in the border extending around the center diamond block.

I claim as my invention:

The ornamental design for a textile fabric, substantially as shown and described.

VIRGINIA HAMILL.
